[57] **CLAIM**

The ornamental design for a adjustable, magnetically
mounted warning light for a vehicle, as shown and
described.

DESCRIPTION

FIG. 1 is a perspective view of a adjustable, magnetically
mounted warning light for a vehicle showing the
new, original and ornamental design;

FIG. 2 is a front elevation view thereof;

FIG. 3 is a left-side elevation view thereof;

FIG. 4 is a rear elevation view thereof;

FIG. 5 is a righthand side elevation view thereof;

FIG. 6 is a bottom plan view thereof;

FIG. 7 is a top plan view thereof; and,

FIG. 8 is a perspective view thereof on a reduced scale,
the fragmentary vehicle and second light being shown
in broken lines for illustrative purposes only.
